UNITED STATES PATENT OFFICE.

LINDSLEY SCHEPMOES, OF HASBROUCK HEIGHTS, NEW JERSEY, ASSIGNOR TO THE SAFETY CAR HEATING & LIGHTING CO., OF NEW YORK, N. Y., A CORPORATION OF NEW JERSEY.

DESIGN FOR A LAMP-BOWL.

43,121.

Specification for Design.

Patented Oct. 8, 1912.

Application filed August 23, 1911. Serial No. 645,672. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Lamp-Bowls, of which the following is a specification.

The nature of my design is fully illustrated in the accompanying drawing, to which reference is made, and in which—

Figure 1 illustrates a perspective view of the design; and Fig. 2 a plan view on a reduced scale.

My design comprises a generally concavo-

convex glass bowl the walls of which extend from the edge or rim of the bowl in symmetrical curved planes converging toward the axis of symmetry, said walls being disposed at angles to each other so that a section at right angles to the axis of symmetry is polygonal, having the contour and relative proportion of parts shown.

I claim:

The ornamental design for a lamp bowl as shown and described.

LINDSLEY SCHEPMOES.
